INDIANA, ASSIGNEES TO DELTA ELECTRIC COMPANY, OF MARION, INDIANA, A
CORPORATION OF INDIANA.

PORTABLE ELECTRIC LAMP.

1,128,945.

Specification of Letters Patent. Patented Feb. 16, 1915.

Application filed February 6, 1914. Serial No. 816,894.

To all whom it may concern:

Be it known that we, JOHN J. BROWNRIGG, HARRY HENDERSON, and ARTHUR E. CASE, residents of Marion, in the county of Grant and State of Indiana, respectively, have invented new and useful Improvements in Portable Electric Lamps, of which the following is a full, clear, and exact description.

10 The invention relates to portable electric lamps.

The invention designs to provide a handy portable electric lamp, which is made up of few parts and in which a common form of dry battery may be employed.

15 The invention further designs to provide an improved portable electric lamp which is adapted to be operated by a common form of dry battery which has both poles disposed at the top or one end thereof and in which the poles are positively connected to the lamp and electrical conductors for the lamp.

20 The invention further designs to provide a new and improved means for connecting the switch in the cover to the battery in the casing.

25 The invention further designs to provide a new and improved portable lamp with a handle thereon in which the switch for the lamp circuit may be easily manipulated by the operator's thumb while grasping the handle in the same hand.

30 The invention further designs to provide a new and improved form of lamp.

In the drawings: Figure 1 is a vertical sectional view of the device. Fig. 2 is a plan view of the bottom of the cover. Fig. 3 is a section taken on the line 3—3 of Fig. 1.

35 The lamp comprises a casing 10 for receiving a common form of dry battery 11 in which both poles are disposed at the top or at one end thereof, a cover 12, mounted on which is the lamp 13 and for which it forms a support, said cover being adapted to fit over the top of the casing 10, and means for electrically connecting the lamp to the battery comprising a switch 14 and flexible conductors from the battery to the 40 switch and cover.

45 The casing 10 comprises a cylindrical body having a handle 15 secured to the side thereof, said casing being of a diameter

sufficient to receive therein, a common dry battery 11. The casing is creased adjacent the top as at 16, to provide a seat for the lower edge of the cover 12, and is notched at 17 to provide for the projecting end of the lamp socket.

50 The cover 12 comprises a flat top and a cylindrical portion forming a depending annular flange which is adapted to fit over the upper end of the casing. The electric lamp 13 on the cover is secured thereto by a socket 18. A lamp hood 19 is secured to 55 socket 18 and projects from the side of the cover. The socket 18 is provided with threads 20 for receiving the threaded end of the base 21 of the lamp 13 and which projects within the confines of said annular flange.

55 The lamp hood 19 is funnel shaped and is adapted to receive a funnel shaped reflector 22 having a concave conical reflecting surface, which reflector is secured in position within the casing 19 by a split spring ring 23. The lamp hood or casing 19 is provided with a flange portion 26 to provide a suitable seat for a lens 24. The lens 24 rests upon the ring 23 and is held in position within the lamp hood 19 adjacent its outer edge by a split ring 25.

60 The switch 14 comprises a resilient contact 27 fixedly secured to the insulating plate 28 which is riveted to the cover 12 on the inside thereof, and a movable switch member 29 which is pivotally secured to the plate 28 at 30.

65 The resilient member 27 is bent downwardly as at 31 so as to contact with tip-contact 32 of the bulb 21 and is secured to the plate 28 by rivets 33. The inner end of contact 27 is bent downwardly as at 34 so as to receive the end 35 of the movable member 29. Switch-member 29 extends 70 through the rear of the cover 12 and is insulated therefrom, by plates 28 and 36. The extended end 37 of the contact 29 is bent downwardly so as to provide means whereby the switch may be operated by the thumb or forefinger.

75 The means for electrically connecting the switch to the battery consists of two flexible insulated conductors 38 and 39. Conductor 38 is secured at one end to the cover 12, and detachably secured at the other end

to the negative terminal 40 of the battery 11. Conductor 39 is detachably secured to the positive terminal 41 of the battery 11 and runs up through the insulation plate 28 5 as at 42 and is connected to the movable switch member 29 at its pivot point.

To assemble the lamp or to replace an ordinary battery having both of its poles at the top, all that is necessary is to connect 10 the conductors 38 and 39 to the terminals 40 and 41, the conductors being of sufficient length to permit this to be done and then press down the cover until the lower edge contacts with flange 16. The lamp may 15 then be carried by handle 15 in either hand and the switch set at "on" or "off" position by a movement of the thumb against the extension 37.

When the contact has been moved so that 20 its end 35 passes under the inner end of contact 27 the following circuit is established to light the lamp: battery 11, terminal 40, conductor 38, cover 12, socket 18, lamp 21, contact 27, contact 29, pivot 30, 25 conductor 39, terminal 41, battery 11. In its off position the circuit is broken through contacts 27 and 29 by moving contact 29 out of engagement with contact 27.

It will be observed, from the above description, that the operating mechanism is carried entirely by the cover or flanged support, and that by projecting the base of the lamp within the confines of the flange of the support, the contact of the lamp is made 35 within said flange below the top of the support. Thus, the hood of the lamp can be secured to the outside of the flange, which provides a very simple and inexpensive structure.

40 The invention is not to be understood as restricted to the details set forth, since these may be modified within the scope of the appended claims without departing from the spirit and scope of the invention.

45 Having thus described the invention what

we claim as new and desire to secure by Letters Patent, is:

1. A device of the class described, comprising a dry battery having both of its poles at one end, a lamp support of conducting material adjacent the pole end of said battery, an electric lamp carried by said support and in circuit therewith as to one of its terminals, a contact member insulated from said support and with which the other lamp terminal is electrically connected when inserted to position, a switch member on said support for controlling the circuit, and flexible electrical connections fixedly and detachably connected with the poles of the battery and electrically connected to said support and said switch member, respectively.

2. A device of the character described, comprising a dry battery, an electric lamp, 65 a support provided with a downwardly projecting annular flange, said lamp being removably fixed to said flange with its base lying within the confines thereof, and electrical connections to said lamp fixed to said support within said annular flange and whose free ends are adapted for fixed engagement with the poles of said battery.

3. A device of the character described, comprising a casing, a battery removably 75 disposed therein, a cap for said casing provided with a downwardly projecting annular flange, an electric lamp removably fixed to said flange with its base lying within the confines thereof, and electrical connections 80 fixed to said cap within said annular flange and whose free ends are adapted for engagement with the poles of said battery and said lamp.

JOHN J. BROWNRIGG.
